Fig. 4

Fig. 5

Fig. 1 is a perspective view of a tableware drying pan or similar article, showing our new design;

Fig. 2 is a top plan view thereof;

Fig. 3 is a medial longitudinal vertical sectional view taken along the line 3—3 of Fig. 2;

Fig. 4 is a bottom plan view thereof; and

Fig. 5 is an end elevational view thereof.

We claim:

The ornamental design for a tableware drying pan or similar article, substantially as shown.
